UNITED STATES PATENT OFFICE.

WILLIAM E. EMIG, OF YORK, PENNSYLVANIA, ASSIGNOR OF ONE-HALF TO ERWIN S. BAER, OF PHILADELPHIA, PENNSYLVANIA.

ICE-CAN COVER.

1,233,565.

Specification of Letters Patent. Patented July 17, 1917.

Application filed May 19, 1916. Serial No. 98,581.

To all whom it may concern:

Be it known that I, WILLIAM E. EMIG, a citizen of the United States, residing in York, in the county of York, State of Pennsylvania, have invented certain new and useful Improvements in Ice-Can Covers, of which the following is a specification.

My invention relates broadly to ice cans employed in the manufacture of ice or more particularly to what is generally known as a cover for such cans which is employed for the purpose of catching and holding the sediment present in the raw water from which the ice is manufactured.

In the manufacture of ice raw water is placed in cans which in turn are placed in refrigerating or freezing tanks. The water in these cans begins to freeze at the outer sides against the walls thereof. Usually means is provided for sending a blast of air through the water to agitate the same and cause movement thereof against the inner surface of the ice as it is formed, which prevents the settling of the sediment in the water against these sides and consequently prevents the freezing of the same within the ice as it is formed. The air flowing upwardly through the water not only agitates the same but causes an upward movement of the sediment therein toward the top of the water in the can.

One object of my invention is to provide a cover having means to permit the water to pass therethrough and also having means which is adapted to receive an overflow of water and retain the sediment therein and is also provided with means whereby the water may flow out of the said sediment retaining means back into the body of water within the can. As a result of such arrangement I have been able to bring about a great economy in the cost of manufacture.

A further object of my invention is to provide a cover which may be more cheaply and economically constructed than other covers of which I am aware and thereby decrease the manufacturing cost of the same. It will be seen therefore that my invention accomplishes an economy not only in the matter of the cost of manufacture of the cover itself, but also in the cost of production of ice in that it decreases the amount of waste water resulting from its use.

In order that my invention may be more readily understood and its practical advan-

tages more fully appreciated, reference should be had to the accompanying drawing in which I have illustrated certain forms of convenient embodiments thereof. It will be understood however that changes in the details of construction may be made within the scope of my claims without departing from my invention.

In the drawing,—

Figure 1 is a vertical central longitudinal sectional view of a can containing water and provided with a cover embodying my invention.

Fig. 2 is a similar view with the water in the can partially frozen.

Fig. 3 is a top plan view of a can and a cover embodying my invention.

Fig. 4 is a transverse sectional view taken on the line 4—4 of Fig. 3; and

Fig. 5 is a top plan view of a can and a cover, the latter showing a modified construction embodying my invention.

Referring to the drawing, 1 designates a can the side walls of which are slightly flared as depicted in the drawing, and 2 designates a pipe through which a blast of air is supplied to the bottom of the tank.

In Fig. 1, the can is shown as containing a suitable quantity of raw water 3, while in Fig. 4 the can is shown as containing a portion of ice 4 and water 3.

5 designates the base of the cover which is suspended below the top of the can by means of suitable brackets 6 having lateral projections 7 at the upper ends which rest upon the top edges of the walls of the can. The base 5 of the cover should fit loosely within the upper portion of the can as shown.

The said base is provided with a receptacle 8 upon its upper side formed by means of the flange like outwardly flaring walls, as shown. The lower edges of said walls are provided with lateral flanges 9 which are riveted to the base 5. It will be understood that the flaring flange like walls may be otherwise secured to the base 5, as by soldering. The said base 5 is provided with an opening 10 which extends transversely thereof and which may be situated, as shown in Figs. 1 to 4 inclusive at one end portion of the receptacle 8.

A flange 11 situated at or adjacent to the inner edge of the opening 10 extends transversely of the receptacle 8 and is of a height 110

considerably less than that of the walls of said receptacle 8, as is clearly shown in the drawing. The opposite ends of the flange 11 are square, that is to say, they are straight so that between the said ends and the adjacent side walls of the said receptacle there are spaces terminating at their lower ends in acute angles 15 as best shown in Fig. 4 of the drawing. It will be seen that between the flange 11 and the side walls and one end wall of the receptacle 8, a chamber is formed into which the water is discharged as it pours over the top edge of the flange 11.

In Fig. 5 of the drawings the construction is identical with that shown in the preceding figures, except that the opening 10^a is situated practically at the center of the receptacle 8 and that there are two flanges 11^a, one at each side of the opening 10^a, so that the water which passes up through the opening 10^a is discharged in opposite directions over the top edges of both flanges 11^a.

In operation the cans are supplied with raw water, being filled to a point such that when the covers are placed in position there-in the bases thereof will occupy positions a half-inch, more or less, above the top surface of the water. As the water freezes it expands, the expansion being sufficient to bring the top of the ice which is formed into contact with the said base. As already stated, the water first begins to freeze at its outer side or surface. The passage of the blast of air through the water agitates it to cause movement of the water against the inside surfaces of the ice as it is formed, thus preventing lodgment of sediment and objectionable foreign matters upon the said walls. As the ice continues to form the top surface of the water rises until it also contacts with the base 5 of said cover and passes upwardly through the opening 10 or 10^a and owing to the passage upwardly through the water of the blast of air as described, the water is caused to splash or flow over the top edge of the flange 11 or the top edges of the flanges 11^a, as the case may be. The sediment which passes over the top of the said flange or the tops of said flanges, as the case may be, is retained in the chamber between the said flange or flanges and the opposing end or ends of the receptacle, but a portion, more or less, of the water thus caused to overflow returns around the opposite edges of the flange 11 or flanges 11^a to the body of water in the can. It follows that when the body of water in a can is frozen only a very small proportion thereof has lodged in the chamber of said receptacle 8, but all or substantially all of the sediment will have found lodgment therein.

I claim:—

1. A cover for ice cans comprising a base plate member having a receptacle upon the top side thereof, said plate having an open-

ing extending therethrough within the area of said receptacle and a flange-like partition wall projecting upwardly from said base plate and extending between and terminating adjacent to opposing walls of said receptacle, said flange-like partition wall being situated adjacent to said opening.

2. A cover for ice cans comprising a plate member having a receptacle upon the top side thereof, the walls of said receptacle flaring upwardly and outwardly, said plate having an opening extending therethrough within the area of the bottom of said receptacle and said plate also having a flange-like projection extending upwardly from said base and extending between opposing walls of said receptacle, the opposite end of said flange-like projection extending substantially at right angles to the plane of said base plate whereby angular openings are provided between the said opposite ends and the opposing walls of said receptacle, and the said flange-like projection being situated adjacent to said opening.

3. A cover for ice cans comprising a plate member having a receptacle upon the top side thereof, the walls of said receptacle flaring upwardly and outwardly, said plate having an opening extending therethrough within the area of the bottom of said receptacle and said plate also having a flange-like projection extending upwardly from said base and extending between opposing walls of said receptacle, the opposite ends of said flange-like projection extending substantially at right angles to the plane of said base plate whereby angular openings are provided between the said opposite ends and the opposing walls of said receptacle, said flange-like projection being situated adjacent to said opening and being of a height considerably less than the height of the walls of said receptacle.

4. A cover for ice cans comprising a plate member of a size to fit loosely within the top portion of a can and having means for supporting the said plate member within the top portion of a can, said plate member having a receptacle upon the top side thereof and also having an opening extending therethrough within the area of said receptacle and a flange adjacent to an edge of said opening, said flange extending transversely of said receptacle and terminating adjacent to the walls thereof.

5. A cover for ice cans comprising a plate member adapted to fit loosely within the upper portion of a can having means for supporting the said plate member within the upper portion of such can, said plate member having a receptacle upon its top side, the walls of which flare outwardly therefrom and said plate having an opening extending therethrough within the area of the bottom of said receptacle and also hav-

ing an integral flange-like projection formed by bending up a portion of the metal of the plate into a plane extending transversely of the plane of said plate, the 5 opposite ends of said flange-like projection terminating at points adjacent to opposing walls of said receptacle, the edges of said ends forming acute angles with the opposing portions of the walls of said receptacle, substantially as described.

10 6. A cover for ice cans comprising a plate member adapted to fit loosely within the upper portion of a can, a receptacle upon the top side of said plate member, the portion of the said member within the walls of said receptacle constituting the bottom

of the latter, and said plate member having an opening extending therethrough which opening is situated substantially at the central portion of the bottom of said receptacle, 20 and said plate member being provided with flange-like projecting portions situated adjacent to opposing edges of said opening and extending transversely of the said receptacle, the opposing ends thereof being 25 situated adjacent to the opposing walls of the said receptacle.

In testimony that I claim the foregoing as my invention, I have hereunto signed my name this 18 day of May, A. D. 1916.

WILLIAM E. EMIG.
